UNITED STATES PATENT OFFICE

EDWARD H. LEHMAN, OF CHICAGO, ILLINOIS, ASSIGNOR TO W. H. MINER, INC., OF CHICAGO, ILLINOIS, A CORPORATION OF DELAWARE

CAR CONSTRUCTION

Application filed December 26, 1929. Serial No. 416,390.

This invention relates to improvements in car construction.

One object of the invention is to provide a sectional, combined locking and center pin 5 for connecting the body and truck bolsters of railway cars, having a detachable head member at one end thereof.

Another object of the invention is to provide a combined locking and center pin comprising a pair of outer members and a spreading member, the outer members having shouldered engagement with the body and truck bolsters of a car to prevent separation thereof, wherein the shouldered engagement 15 with one of the bolsters is obtained by an adjustable and detachable head member on said outer members, thereby facilitating application and removal of the pin.

A still further object of the invention is 20 to provide a center pin of the character described in the preceding paragraph, wherein the adjustable head member is in the form of a nut threaded to the outer members and is locked against removal by the filler member having shouldered engagement therewith.

Other objects of the invention will more clearly appear from the description and claims hereinafter following.

30 Figure 1 is a top plan view of my improved center pin proper. Figure 2 is a vertical sectional view through the truck and body bolsters of a railway car illustrating my improved center pin applied thereto, the section corresponding substantially to the line 2-2 of Figure 1. Figure 3 is a bottom plan view looking upwardly in Figure 2, the truck bolster being omitted in this view. And Figure 4 is an elevational view of a combined 35 filler and locking member employed in connection with my improved center pin.

In said drawings, 10 indicates the body bolster and 11 the truck bolster of a railway car. The body and truck bolsters are of well 45 known design, and are provided with the usual alined center pin receiving openings 12 and 13 respectively. The body bolster has the usual downwardly projecting bearing member 14 on the lower side thereof cooperating with a bearing block 15 mounted on

top of the truck bolster. The bearing block 15 is provided with an upstanding annular rib or flange 16 which engages within a pocket 17 provided on the bottom side of the body bolster. Beneath the opening 13 of the truck 55 bolster, a pocket 18 is provided which accommodates the head at the bottom end of the center pin.

My improved center pin proper comprises broadly a pair of outer members A—A, a 60 combined filler and locking member B and a detachable head member C.

The two outer members A—A are of like design, each comprising a shank portion extending through the pin receiving openings 65 of the bolsters and the block 15 and a partial head 19 at the upper end thereof. The partial head 19 is in the form of an arcuate flange laterally projecting from the member A. As most clearly shown in Figure 2, the flanges 70 19—19 of the two members A engage the upper surface of the body bolster and thereby prevent dropping of the center pin and also serve in conjunction with the retaining means at the lower end of the pin for preventing separation of the bolsters. The shank of each member A is reduced at the bottom end, as indicated at 20, said reduced portion being screw threaded as shown, the screw threads on one member A forming a 75 continuation of the threads of the other member.

The spreading member B is in the form of an elongated plate of substantially the same width as the diameter of the pin receiving 80 openings of the bolsters. As most clearly shown in Figure 4, the member B is of substantially uniform width throughout its height and has a pair of laterally projecting lugs 21—21 at opposite sides at the upper 85 end thereof. The lugs 21 are of substantially the same height as the flanges 19—19 of the members A and form with said flanges 19—19 a continuous annular head member. When the filler member B is assembled with 90 the members A by being inserted therebetween, the same serves to hold the members A—A separated and together with said members forms the complete center pin. As shown in Figures 1 and 2, the complete pin 95 100

is of substantially cylindrical cross section, the outer surfaces of the members A—A being curved to correspond with the walls of the pin receiving openings of the bolsters.

5 In addition to serving as parts of the head of the pin, the lugs 21—21 prevent the member B from dropping through the openings of the bolsters.

10 The head member C, which is located at the bottom end of the pin, is in the form of a hexagonal nut and is screwed onto the threads 20—20 of the members A—A. As most clearly shown in Figure 3, the nut C is slotted interiorly at diametrically opposite 15 sides as indicated at 22—22. The slots 22—22 are adapted to receive the bottom end of the filler member B, whereby the nut is locked against rotation with respect to the members A—A. As shown in Figure 2, the filler member is of greater length than the outer members A of the pin and projects a slight 20 distance beyond the bottom ends of these members.

25 The screw threaded member C provides for adjustment in length of the pin, that is for adjustment of the distance between the heads at the opposite ends of the pin. In adjusting the head C, the filler member B is raised so as to withdraw the same from the slots 30 22—22 of the nut, whereupon the nut may be rotated to adjust the same either inwardly or outwardly along the threads of the members A. When the nut has been adjusted to the 35 desired extent, the slots 22, having been brought into alinement with the filler plate member, the latter is pushed downwardly into engagement with said slots, thereby locking the head C against rotation with respect to the pin proper.

40 In order to facilitate removal of the filler member and the outer members of the pin, each of these members is provided with an eye at the upper end of the same, the eye of the filler member being indicated by 23 and the eyes of the outer members being indicated by 24—24.

45 In applying my improved center pin to the bolsters 10 and 11, the sections may be applied either through the top of the body bolster or through the bottom of the truck bolster. When applied through the body bolster, the outer sections A—A together with the filler member B may be inserted simultaneously, but the member B is raised slightly with respect to the members A so that the lower end thereof will clear the reduced threaded portions of the members A. The head C is then screwed onto the lower ends 50 of the members A and the slots thereof registered with the filler member B, whereupon the latter is forced downwardly so as to enter the slots and lock the nut or head C against removal. In applying the pin through the opening of the truck bolster, the two outer

members A are first inserted, the flanges 19—19 being of such a size that they will pass through the pin receiving openings of the bolsters when the filler member B is omitted. After the two members A have been completely inserted, the same are spread apart so as to engage the flanges 19—19 at the upper ends thereof over the top of the body bolster. The filler member is then applied by inserting the same between the outer members A—A, the same being entered from the top of the body bolster. The head C is then applied to the bottom ends of the members A and locked thereto, as hereinbefore pointed out.

55 In separating the bolsters, the pin is removed by first lifting the filler member to clear the nut or head C, and then rotating the nut so as to unscrew the same. After removal of the nut or head C, the sections may all be withdrawn through the body bolster or the filler member B may be first withdrawn upwardly through the body bolsters and the members A—A dropped through the 60 openings of the body and truck bolsters.

65 I have herein shown and described what I now consider the preferred manner of carrying out my invention, but the same is merely illustrative and I contemplate all changes and modifications that come within the scope 70 of the claims appended hereto.

I claim:

1. In car construction, the combination 75 with body and truck bolsters having alined center pin receiving openings; of a center pin extending through said openings, said pin comprising a pair of outer members and a central spreading member, each of the outer members having a member at one end having shouldered engagement with one of said bolsters; and a detachable head member at the 80 other end of said first named members, having shouldered engagement with the other bolster, said detachable head member being 85 locked against removal by said spreading member.

100 2. In car construction, the combination with body and truck bolsters having alined center pin receiving openings; of a center pin extending through said openings, said pin comprising a pair of outer members and a central spreading member, each of the outer members having a member at one end having shouldered engagement with one of said bolsters; and an adjustable and detachable head member secured to the other end of said first 105 named members and having shouldered engagement with the other bolster.

110 3. In car construction, the combination with body and truck bolsters having alined center pin receiving openings; of a center pin extending through said openings, said pin comprising a pair of outer members and a central spreading member, each of the outer 115 members having a member at one end having shouldered engagement with one of said bolsters; and an adjustable and detachable head member secured to the other end of said first named members and having shouldered engagement with the other bolster.

120 4. In car construction, the combination with body and truck bolsters having alined center pin receiving openings; of a center pin extending through said openings, said pin comprising a pair of outer members and a central spreading member, each of the outer 125 members having a member at one end having shouldered engagement with one of said bolsters; and an adjustable and detachable head member secured to the other end of said first named members and having shouldered engagement with the other bolster.

members having a member at one end having shouldered engagement with one of said bolsters; and a head member threaded on the other end of said members and having shouldered engagement with the other bolster, said 5 filler member having engagement with said head member to lock the same against removal.

4. In car construction, the combination with body and truck bolsters having alined 10 center pin receiving openings; of a pair of outer members each having a shank extending through said openings, said members having head portions at one set of ends having shouldered engagement with one of said bolsters; a combined filler and spreading member 15 interposed between said outer members for maintaining said members in shouldered engagement with the corresponding bolster; and a head threaded on the other set of ends 20 of said outer members and having shouldered engagement with the other bolster, said filler member interlocking with said head when the parts are assembled to lock the head member against removal.

25 In witness that I claim the foregoing I have hereunto subscribed my name this 23rd day of December, 1929.

EDWARD H. LEHMAN.
